ILLUMINABLE MERCHANDISING DISPLAY STAND

Lawrence W. Patterson, Santa Ana, Calif., assignor to Spring-A-Way Displays of California, Inc., a corporation of California

Filed June 19, 1959, Ser. No. 56,425

Term of patent 14 years

(Cl. D80—9)

Fig. 1 is a front perspective view of an illuminable merchandising display stand embodying my new design; and

Fig. 2 is a perspective view from the rear thereof.
I claim:

The ornamental design for an illuminable merchandising display stand, as shown.
